DESIGN FOR A TIE CLIP

Charles du B. Arcularius, New Canaan, Conn.

Application August 15, 1940, Serial No. 94,434

Term of patent 7 years

To all whom it may concern:

Be it known that I, Charles du B. Arcularius, a citizen of the United States, residing at New Canaan, in the county of Fairfield and State of Connecticut, have invented a new, original, and ornamental Design for a Tie Clip, of which the following is a specification, reference being had to the accompanying drawing, forming part thereof.

I claim:

The ornamental design for a tie clip, substantially as shown.

CHARLES DU B. ARCULARIUS.
